UNITED STATES PATENT OFFICE

ROLLAND G. WILLIAMS, OF BRANFORD, CONNECTICUT, ASSIGNOR TO MALLEABLE IRON FITTINGS COMPANY, OF BRANFORD, CONNECTICUT, A CORPORATION OF CONNECTICUT

HIGHWAY GUARD FENCE

Application filed April 30, 1931. Serial No. 534,092.

My invention relates to highway guard fences, such as are made of iron in tubular form and are utilized on steep grades, and has for its object to simplify the construction 5 of guard fences of this type.

In the accompanying drawing

Figure 1 is an elevation of a part of a fence constructed in accordance with my invention,

10 Figure 2 is a view looking in the direction of line 2—2 of Figure 1,

Figure 3 is a view looking in the direction of line 3—3 of Figure 2, and

15 Figure 4 is a section at the line 4—4 of Figure 1.

Similar numerals of reference denote like parts in the several figures of the drawing.

1 are the fence posts mounted in any suitable manner, and 2 are the fence rails. 20 3 is a metal socket that embraces the post and is formed at its front with a projecting annulus 4 of truncated conical shape.

25 5 is a metal socket that embraces the fence rail and has extending from its rear a hub 6 that has a recess 7 adjacent the rail, and whose rear face has a formation complementary to that of the annulus 4. In other words, the rear face of the hub 6 has an annular depression 8 with the inclined sides of which 30 the annulus 4 may have a wedging contact.

In assembling the fence, the socket 3 is slipped over the post and the socket 5 positioned with its annulus 4 within the annular depression 8, and a set screw 9 is driven in 35 the recess 7 through the hub 6 and socket 3, against the post with sufficient force to hold said socket to the post temporarily.

40 The socket 5 is then turned to the desired angular adjustment according to the incline of the rail and the set screw permanently tightened.

45 The tightening of the screw will wedge the annulus of the socket 3 tightly within the annular depression 8, thus firmly securing the two sockets together, and the adjustment

is such that the external junction between the two sockets will be tightly sealed as against moisture.

What is claimed is:

A means for clamping the rods to the posts 50 in highway guard fences consisting of a metal socket for embracing a post having an annulus of truncated cone formation projecting from the front portion, a metal socket for a rod, a recess therein, a hub projecting from 55 its rear portion having an annular depression therein complementary to the annulus, the sides of the annulus and depression having a wedging contact, and a set screw housed within the recess and driven through the hubs 60 and post socket against the post after the rod socket has been adjusted to the desired position.

In testimony whereof I affix my signature hereto.

ROLLAND G. WILLIAMS.
